UNITED STATES PATENT OFFICE

2,560,942

CURTAIN ROD

Ledger D. Ford and Frederick L. Stutz, Sturgis,
Mich., assignors to Kirsch Company, Sturgis,
Mich., a corporation of Michigan

Original application January 10, 1946, Serial No.
640,306, now Patent No. 2,494,697, dated Janu-
ary 17, 1950. Divided and this application No-
vember 21, 1949, Serial No. 128,564

11 Claims. (Cl. 211—105.3)

1

This invention relates to improvements in curtain rods. This application is a division of our application for Letters Patent filed January 10, 1946, Serial No. 640,306, which has become U. S. Patent #2,494,697.

The main objects of this invention are:

First, to provide a bracket and a coacting combined bracket engaging rod tip and threading pilot which facilitates the threading of the rod into a curtain and the mounting thereof on the bracket.

Second, to provide a curtain rod and bracket assembly which is well adapted for the support of curtains at the upper and lower ends thereof and without subjecting the curtain to stretching stresses.

Third, to provide a curtain rod structure having these advantages which is very easily manipulated in the assembling of the combined rod tip and pilot member with supporting brackets.

Objects relating to details and economies of the invention will appear from the description to follow. The invention is defined and pointed out in the claims.

A preferred embodiment of the invention is illustrated in the accompanying drawing, in which:

Fig. 1 is a fragmentary elevational view of a door having a glazed opening therein provided with the curtain rods embodying our invention, various parts being shown conventionally.

Fig. 2 is an enlarged fragmentary view partially in longitudinal section on a line corresponding to line 2—2 of Fig. 1, the curtain being omitted.

Fig. 3 is an enlarged fragmentary front elevational view with the curtain rod partially broken away and partially in longitudinal section.

Fig. 4 is a perspective view of the bracket.

Fig. 5 is a perspective view of the combined bracket engaging rod tip and threading pilot element.

In the accompanying drawing 1 represents a door having a glass panel 2. 3 represents a curtain. The embodiment of our invention illustrated comprisees a curtain rod 4 of oval or non-circular section which may desirably have telescoping sections 5 and 6. The combined bracket engaging tip and threading pilot 7 comprises a convex head 8 desirably of a peripheral shape corresponding substantially to the cross sectional shape or dimensions of the rod; that is, when the rod is of oval section the head is correspondingly of oval section.

The rod tip member has neck portions 9—9 extending from opposite edges thereof, these neck

2

portions being of a width less than the diameter of the head and merging into the convex face of the head. The neck members have integral spring arms 10 extending from their inner ends.

5 These arms are of convex curved section frictionally fitting within the rod; that is, they are in frictional retaining engagement with the rod. The arms are inwardly offset at 11 relative to the neck members, as is clearly illustrated, providing 10 inwardly facing shoulders which abut the ends of the rod and thereby insure the proper positioning of the bracket engaging rod tip member relative to the rod.

Further, this inward offsetting of the rod 15 engaging parts 10 provides an effective guard for the ends of the rod so that the rod may be threaded through suitable pockets provided therefor in the curtain without engaging the fabric. The rod tip member is adapted for en-

20 gagement with the supporting bracket designated generally by the numeral 12 and comprising the base 13 adapted to receive attaching screws 14 and the forwardly projecting arm 15 having a longitudinal slot 16 therein open at its outer end 25 to receive the neck members 9 when they are presented sidewise thereto.

The width of the neck members is such that their edges slidably engage the edges of the slot 16 and the neck members being spaced effectively prevent turning or rotation of the rod relative to the bracket. The inwardly facing portion 17 of the head engages the outer side of the bracket. The bracket is provided with a springable finger or tongue 18 which is outwardly offset from the bottom edge of the slot and springably engages the head of the rod tip member when the parts are in assembled relation as shown in Figs. 2 and 3. This permits the ready engagement of the rod tip members with the brackets merely by presenting the neck members sidewise thereto and forcing into the slots against the thrust of the spring fingers 18.

It is quite common practice to provide windows with curtains supported by rods at the top and bottom. This invention permits the support of the curtains at the top and bottom without placing the curtains under stretching stress as is quite commonly required in installations of this character. Further, exact mounting of the 45 brackets is not required for each curtain, the brackets may be mounted at the upper and lower ends of the window, the curtain prepared to receive the rods, the rod threaded into the upper and lower pockets of the curtain, and the rod 50 assembled with the bracket merely by pushing

their tip members rearwardly into the bracket slots. They can be easily disassembled by an outward pull thereon as the occasion requires for laundering or replacing of the curtain. The rod tip members may be easily and quickly assembled with rods without the aid of screws or other fastenings. When used with rods made up of telescoped sections, the rod sections are effectively held in their proper extended relation.

We have illustrated and described our invention in a highly practical commercial embodiment thereof. We have not attempted to illustrate or describe other adaptations or modifications which we contemplate as it is believed that this disclosure will enable those skilled in the art to embody or adapt our invention as may be desired.

Having thus described our invention, what we claim as new and desire to secure by Letters Patent is:

1. The combination with a bracket provided with an arm having a longitudinal slot therein and a spring finger struck therefrom and disposed in opposed relation to the slot, of a tubular curtain rod, a bracket engaging rod tip having a convex threading pilot head, neck members extending from opposite edges of the head, the width of the neck members being less than the diameter of the head, the neck members having integral springable arms extending therefrom frictionally engaged within the rod, the neck members being disposed sidewise within the slot of the bracket in supporting engagement therewith, the spring finger springably engaging the convex head of the bracket.

2. The combination with a bracket provided with an arm having a slot therein, of a tubular curtain rod, a bracket engaging rod tip having a threading pilot head, neck members extending from opposite edges of the head, the width of the neck members being less than the diameter of the head, the neck members having integral springable arms extending therefrom frictionally engaged within the rod, the neck members being disposed sidewise within the slot of the bracket in supported engagement therewith.

3. The combination with a bracket comprising an attaching base portion and an arm projecting forwardly therefrom, the arm having a longitudinal slot therein opening at its outer end, there being a springable finger projecting forwardly from the bottom of the slot, of a tubular curtain rod, a bracket engaging rod tip comprising a threading pilot head, neck members extending from opposite edges of the head, the width of the neck members being less than the diameter of the head, the neck members having integral spring arms extending therefrom engaged within the rod, the neck members being disposed sidewise within the slot of the bracket in supported engagement therewith with the spring finger springably engaging the head of the tip.

4. The combination with a bracket comprising an attaching base portion and an arm projecting forwardly therefrom, the arm having a longitudinal slot therein opening at its outer end, of a tubular curtain rod, a bracket engaging rod tip comprising a threading pilot head, neck members extending from opposite edges of the head, the width of the neck members being less than the diameter of the head, the neck members having integral spring arms extending therefrom engaged within the rod, the neck members being disposed sidewise within the slot of the bracket in supported engagement therewith.

5. The combination of a bracket provided with an arm having a forwardly facing slot therein and a forwardly projecting springable finger laterally offset in relation to said arm and extending from the bottom of the slot, a curtain rod, and a bracket engaging rod tip comprising a head and neck members engageable within the slot when presented edgewise thereto and of a less width than the width of the head, the neck members having springable rod engaging extensions, the said springable finger springably engaging the head of the rod tip when the neck members are inserted in the slots with the head in side thrust engagement with the outer side of the bracket.

6. The combination with a bracket provided with a forwardly projecting arm having a slot therein opening at its outer end, of a tubular curtain rod, and bracket engaging rod tip having a threading pilot head, neck members extending from the opposite edges of the head and having integral springable arms extending therefrom frictionally engageable within the rod, the neck members being disposed sidewise within the slot of the bracket in supported engagement therewith, the bracket being provided with a spring finger in retaining engagement with the head.

7. The combination with a bracket provided with an arm having an open slot therein and a spring finger opposed to the slot, of a tubular curtain rod, and a bracket engaging rod tip having a threading pilot head, neck members extending from the opposite edges of the head and having integral springable arms extending therefrom engageable within the rod, the neck members being disposed sidewise within the slot of the bracket in supported engagement therewith with the spring finger engaging the head.

8. The combination of a bracket provided with an arm having an open ended slot therein and a laterally and forwardly projecting springable finger extending from the bottom of the slot, a curtain rod, and a bracket engaging rod tip comprising a head, and neck members engageable with said slot when presented sidewise thereto with the spring finger in retaining springable engagement with the head of the tip, said neck members being of less width than the diameter of the head, the neck members having extensions frictionally engaged with the inside of the rod.

9. The combination of a bracket provided with an arm having an open ended slot therein and a spring finger opposed to the slot, a curtain rod, and a bracket engaging rod tip comprising a head, and neck members engageable with said slot when presented sidewise thereto with the spring finger springably engaging the head, said neck members being of less width than the diameter of the head, the neck members having extensions frictionally engaged with the inside of the rod.

10. The combination of a bracket having an open slot therein and a spring finger opposed to the slot, a tubular curtain rod, and a bracket engaging rod tip comprising a head, neck members extending from opposite edges of the head and having integral springable arms extending therefrom frictionally engaged with the inside of the rod, the neck members being disposed sidewise within the slot of the bracket and in supported engagement therewith, with the spring finger retainingly engaging the head of the rod tip.

11. The combination of a bracket having an open ended slot therein, and a spring finger opposed to the slot, a tubular curtain rod, and a bracket engaging rod tip comprising a head, neck mem-

bers extending from opposite edges of the head and having integral springable arms extending therefrom frictionally engageable with the inside of the rod, the neck members being disposed sideways within the slot of the bracket and in supported engagement therewith with the spring finger springably engaging the head.
